John B. Reith

United States Patent Office.

JOHN B. REITH, OF NEW YORK, N. Y.

Letters Patent No. 80,767, dated August 4, 1868.

IMPROVED SOFA AND BED.

The Schedule referred to in these Letters Patent and making part of the same.

TO ALL WHOM IT MAY CONCERN:

Be it known that I, JOHN B. REITH, of the city, county, and State of New York, have invented a new and useful Combined Sofa and Bed; and I do hereby declare that the following is a full and exact description thereof, reference being had to the accompanying drawing, and to the letters of reference marked thereon.

My invention relates to improvements in sofas. The object of this invention is to construct a sofa in such a manner as to form a bed when desired, or a sofa, without trouble or inconvenience.

The nature of my invention consists in forming or making the back seat of the sofa so that it forms or constitutes a movable section, and is hinged in such a manner that such section moves in conjunction with the others.

It also consists in hanging the lower section of the seat on journals, and connecting it to the back section by means of a rod attached to pins or wrists, so that when one of the sections moves, it also causes the other to move; thus the sofa can be readily adjusted from a sofa to a bed.

To enable others skilled in the art to make and use my invention, I will proceed to describe its construction and operation.

The figure represents an end elevation when used as a sofa, and a side elevation when used as a bed.

Letters of like name and kind indicate like parts in the figure.

A represents the frame of the sofa, made of any fancy or ornamental wood, rectangular in form, and of any desired dimensions, which is upholstered to suit the tastes of the manufacturer or consumer.

The portion of the sofa forming the back and seat is made in three sections.

B, representing the back of the sofa, is hung by suitable hinges a short distance from the lower edge of the back to the posts a, at e, so as to allow the back to turn up and down upon the said hinges e.

The seat is composed of two sections, C and D. The lower section, C, is hung on trunnions or journals, e, a short distance to the rear of the centre, which have bearings in each end of the frame A, so as to permit it to be turned over when changing it from a bed to a sofa, and *vice versa*.

The upper section of the seat D is also hinged at d to the section C, so that when the article is used for a bed, it is simply drawn forward, and the outer portion of the said section is supported by the legs E.

The back or section B is connected to the lower section of the seat C by means of a suitable rod, F, at each end of which is a joint, made in any suitable manner, but I usually connect the said rod to the respective sections by securing a wrist or pin, o, to the sections where it is designed to connect them, and having eyes or holes at each end of the rod made to fit said wrists or pins, so connects the said two sections together that when one moves it also moves the others.

G is a pawl or prop, secured to the upper or outer side of section B by a joint, for the purpose of supporting the outer edge of the said section B, when used for a bed. The inner edge of section B is supported by means of cranks, i, secured to the frame of the sofa. When the sections are turned down for a bed, this crank i is brought round over the connecting-rod F in such a manner as to prevent the inner edges of the section from tipping down or becoming depressed, so as to make it uncomfortable to lie upon.

To change the sofa to a bed, all that is required is to raise and at the same time draw forward the section D, while at the same time, by the action of the rod, the section B is pressed back, the middle section C is turned over, and the whole is spread out in such a manner as to form a large and comfortable bed.

It will be observed that the section B stands on an incline, so as to form a very good substitute for a pillow.

The advantages and conveniences of my invention will be readily seen from the fact that it makes a beautiful article of furniture, and a convenient and comfortable bed.

Having thus described my invention, what I claim as new, and desire to secure by Letters Patent of the United States, is—

The sections C and D, in combination with section B and frame A, substantially as herein shown and described, and for the purposes set forth.

JOHN B. REITH.
